UNITED STATES PATENT OFFICE.

THOMAS C. HANSEN, OF CANEY, KANSAS.

MEANS FOR MOLDING BACKINGS FOR ARTIFICIAL TEETH.

Application filed July 12, 1922. Serial No. 574,465.

To all whom it may concern:

- Be it known that I, THOMAS C. HANSEN, a citizen of the United States, residing at Caney, in the county of Montgomery and State of Kansas, have invented certain new and useful Improvements in Means for Molding Backings for Artificial Teeth, of which the following is a full, clear, and exact description.
- 10 My invention relates to means for molding backings for artificial teeth, and has for its object the provision of a celluloid or other hydrocarbon plate to be used as a pattern in molding the backing.
- 15 Another object of the invention is the use of such a hydrocarbon plate in connection with the formation of a solid bridge in dental work.

Other objects and advantages of the invention will be apparent from the following description when taken in connection with the accompanying drawing, in which:

Figure 1 is a perspective view of the prepared roots of two adjacent teeth.

25 Figure 2 is a sectional view of a tooth with a crown pattern thereon.

Figure 3 is a perspective view of such crown patterns.

Figure 4 is a perspective view of the completed pattern for bridge work.

Figure 5 is a similar perspective view looking from a different angle.

Figure 6 is a horizontal section taken on line 6—6, Figure 5.

35 Figure 7 is a section through a mold, showing the bridge pattern.

Figure 8 is a perspective view of the completed bridge, and

Figure 9 is a horizontal section taken 40 through a modified pattern.

Referring to the drawing more in detail, the numeral 1 designates the prepared roots to be crowned and between which a bridge is to be supported. To each of these roots 45 is fitted a hydrocarbon form 2 such as described in my co-pending application Serial No. 550,154. As set forth in said application, a 36-gauge, 24-carat band 3 is fitted over the prepared root in order to get a 50 proper adaptation therefor without causing irritation to the gums, and the form 2 is connected with the band 3 by casting wax 4. The form 2 is lined with casting wax 5 on its interior, and may have wax applied

to the exterior thereof at points desired, as 55 indicated by numeral 6.

The backing for the porcelain tooth 7' is cast integral with the crowns and the mold is made by the use of a hydrocarbon or celluloid plate or form 7 which is provided 60 with a dovetail rib 8 on one face thereof.

After the crown patterns are prepared as above described the backing form 7 is placed between the crown forms and united thereto by casting wax 9, as indicated in Figures 5 65 and 6. Casting wax may be added, of course, at any points desired in order to reinforce the backing and bring the same to the exact shape desired. The completed pattern is then placed in a mold 10 by means 70 of pin 11, and the mold heated to volatilize the casting wax and hydrocarbon forms. After the pattern is volatilized the gold or other casting material is then poured into the mold and the entire bridge, including 75 the two crowns and backing, is cast in one piece, as indicated by numeral 12 in Figure 8.

In the modified form of the invention shown in Figure 9 the numerals 1, 2, 5 and 90 9 represent the same elements shown in Figures 1 to 8, inclusive, but instead of the celluloid plate 7 I have used a celluloid plate 13 provided with the tubular portions 14. This pattern is placed in the mold in the 85 manner previously described and the finished bridge will be provided with two apertures for receiving the pins of the fac- ing which will be cemented to the backing.

From the foregoing description it will be 90 seen that I have provided a novel article and method for casting bridge work in one piece which presents an advantage over the soldering method, in that shrinkage and ex- pansion are eliminated. Furthermore, there 95 is a great saving in time in assembling and finishing the backing and crowns. It should also be noted that this bridge may be cast hollow, if desired, and filled on the lingual surface with synthetic porcelain, cast por- celain or any other material to save gold.

In accordance with the patent statutes, I have described what I now believe to be the best embodiment of the invention, but I do not wish to be understood thereby as limit- ing myself or the scope of the invention, as many changes and modifications may be made without departing from the spirit of

the invention; all such I aim to include in the scope of the appended claims.

What I claim as new and desire to secure by Letters Patent is:

- 5 1. The method of forming a pattern for bridge work which includes fitting hydrocarbon crown forms to the prepared roots and uniting a hydrocarbon plate to the crown forms.
- 10 2. The method of forming a pattern for bridge work which includes preparing crown forms for the adjacent teeth, placing

a hydrocarbon backing form between the crown forms and uniting the crown forms and backing form by casting wax.

3. The method of forming a solid gold bridge which includes preparing crown forms for the adjacent teeth, securing a hydrocarbon backing form between the crown forms, inserting the bridge pattern in a mold, pouring in the molding material, heating the mold to volatilize the pattern, and pouring in molten metal.

THOMAS C. HANSEN.
